(57) **CLAIM**

The ornamental design for a tire, as shown and described.

DESCRIPTION

The patent or application file contains at least one drawing executed in color. Copies of this patent or patent application publication with color drawing(s) will be provided by the Office upon request and payment of the necessary fee.

1. Tire

1.1 : Front

1.2 : Back

1.3 : Left

1.4 : Right

1.5 : Top

1.6 : Bottom

1.7 : Perspective

1.8 : Enlarged

The use of the present design product: the design product is used for vehicle tires; main designing features of the present design product depend on the tread pattern of the product; the picture or photo best showing main designing features of the present design product: perspective view; the red box with the indication "A" shown in reproduction 1.1 is an enlarged view of the tire shown in reproduction 1.8.
